UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 15,578, dated November 25, 1884.

Application filed October 1, 1884. Term of patent 3½ years.

To all whom it may concern:

Be it known that I, JOHN QUINCY REED, of the city, county, and State of New York, have invented and produced a new and original 5 Design for a Pattern of a Girl's Costume, (numbered 9,472;) and I do hereby declare that the engraved prints accompanying this specification convey to any one accustomed to using paper patterns a clear understanding of how 10 a garment made up by the pattern will appear. The design shows a side-plaited skirt displaying a box-plait at the center of the front, a high-necked body portion, a low-necked 15 body portion flaring in fancy curved outline from the shoulders in front, where it exhibits cross-straps extending alternately from under the opposite front edges, and showing their

opposite ends pointed and fastened on the outside, the same body portion also displaying a fitted back that outlines a low fancy 20 pompadour at the neck, a sash-drapery that appears to encircle the top of the skirt in full folds and form a large bow at the back, and coat-sleeves that exhibit a gathering and a high roll at the shoulder. 25

What I claim as my invention, and desire to secure by Letters Patent, is—

The design for a girl's costume, as shown in the engraved prints accompanying this specification.

JOHN QUINCY REED.
